PROCESS OF FORMING A CLOSURE ON A
COLLAPSIBLE TUBECharles J. Westin, Philadelphia, Pa., assignor to
F. J. Stokes Machine Company, Philadelphia,
Pa., a corporation of Pennsylvania

Application June 21, 1933, Serial No. 676,912

2 Claims. (Cl. 113—121)

This invention relates to improvements in closures for collapsible tubes such as are used for pasty products. The tubes are usually made of some suitable soft metal or alloy but might be 5 of celluloid or paper. These tubes are usually filled and then have one end closed by folding or applying a clip to the folded end of the tube. A purpose of my invention is to provide a tube 10 having portions adjacent that end which is to be closed which portions are formed by the spreading or bending of the walls of the tube during the closing or folding operation at that end. These portions can conveniently consist of 15 curved or arcuate steps or arches in the walls of the tube.

The tubes which form the subject matter of this application may conveniently be made in the tube cups which are illustrated and described in my co-pending application for Letters Patent 20 on a Tube closing machine, filed June 21, 1933, Serial No. 676,911.

Another purpose of my invention is to produce a closed tube which will hold a volume of the maximum amount of material possible for a given 25 size of tube. This is accomplished by keeping the circular section of the tube practically constant all the way to the end of the tube, allowing only a very short portion of taper in order to get the necessary length of flat part of the tube walls at 30 the end to form the required number of folds in closing it.

By closing tubes according to the new and 35 novel process here described, a tube is produced, which will hold ten to fifteen per cent more material than a tube closed in the old way. In other words, the present standard tube used to hold a certain amount of material can be $\frac{3}{8}$ inch to $\frac{1}{2}$ inch shorter and still provide ample room for the same volume of material if closed by the new 40 method. This means a considerable saving; taking for example, with a one inch tube being filled at the rate of forty per minute, eight hours a day, or one hundred and thirty gross per day, the saving would amount to \$11.83 a day if a $\frac{1}{2}$ inch shorter tube was used and with tin at 35¢ a 45 pound. The saving on the continuous production of one year, counting two hundred and fifty operating days, would amount to \$2,957.50. The saving is, of course, in proportion to the size of 50 the tube used. It should also be noted that this saving is only figured on the metal used in the tube and at the present low market price of tin. Other items, of course, also enter into the saving such as the use of smaller cartons and packing 55 cases, etc.

Heretofore, it has been the practice to place the tubes into short holders or tube-cups, which hold the tubes at the capped end 2 while they are being conveyed from one station to another in the filling and closing machine. Standard 5 practice has been to make the recess of the tube-cup, into which the tube is placed, about the same depth as the diameter of the tube. Tubes held in these cups will, when being flattened at the open end to provide the necessary flat portion required for the closing folds, spread out 10 sidewise, changing their shape gradually from a perfect cylinder at the breast or capped portion to the flat section at the folds, the sides tapering out from the breast to the end of the folds 15 while the face and back taper in from the breast to the folds. The rate at which a tube naturally spreads and flattens varies for different materials used in the tube walls and is also slightly affected by the stiffness of the content. This 20 spreading and flattening of the tube body decreases the volume. It should be noted that the tube must be held fairly rigid in the cup, so as to prevent wobbling as they are conveyed from one station to another. Any freedom in the cups 25 would permit the tube to lean over and the folds made on such a tube would not be square with the axis of the tube, causing defective folds and rejected products. Although the tube-cups were shallow, it was necessary to machine them with 30 a groove of three to six degrees taper in that portion of the recess, where the sides of the tubes would form or spread as the tube was flattened. The practice has sometimes been to mill out the tube-cup bell-shaped, allowing only 35 about one-quarter of the depth from the bottom to remain straight, and relying on this short straight portion to keep the tubes in a perpendicular position. Without the taper or bell-shape in the cup, as referred to above, the tubes 40 would have objectionable dents or wrinkles in the sides at the end of the straight part of the recess in the cups. It is evident that the straight portion in the recess has to be a fairly snug fit on the tube in order to hold the tubes of any 45 length up to ten to twelve inches rigidly in a perpendicular position so as to avoid bad folds. On the other hand, it is, of course, impossible to maintain exactly the same diameter on a lot of tubes because of the wear in the dies, and because 50 of the varying thickness of the enamel and lacquer added in lithographing the tubes, and it was therefore necessary to allow a few thousandths of an inch clearance in the straight portion of the tube-recess, so that the operator would 55

be able to push the tube down against the shoulder or bottom of the recess. The close fit required in the tube-cup, and the varying diameters found in the manufacture of tubes has always caused considerable trouble to the operator in properly placing the tubes in the machines at the desired production rate.

By my invention the above difficulties are entirely eliminated. The tube-cups are made in proportion to the length of the tube and support the tube close up to the fold. The tubes being supported practically throughout their entire length do not have to be held rigid in the cup as previously was necessary, but a clearance as large as $\frac{1}{16}$ inch is permissible for a one inch diameter tube, this clearance being less for smaller tubes and larger for tubes of larger diameters.

In connection with this full length tube-cup, of my co-pending application, referred to above, it is, however, necessary to use what is known as a preformer, as shown in my co-pending application, in order to get uniform results and maintain a definite shape of the tube as it is being closed.

By this novel and new arrangement of holder and former, a definite shape can be given to the tube as it is being closed, and this shape remains uniform at all times regardless of the type of material used in the tube walls or the contents of the tubes. To get the maximum material into a tube the support or top of the tube-cup should come to about $\frac{1}{8}$ of the diameter from the top of the tube. This allows sufficient distance for flattening the tube for the required number of folds and permits the tube to form into a pleasing Gothic arc in outline, when looking at the tube from the side of the tube or end of the fold.

To prevent unsightly wrinkles or dents in the tube walls below the folds as well as in the folds themselves, it is necessary to spread the open end of the tube. As the open end of the tube is spread out by the preformer the sides of the tube are held or supported by the top of the tube-cup and the break between the straight cylindrical side of the tube and the spread out portion above the top of the tube-cup forms itself into an arcuate fold or step. This fold or step becomes more pronounced as the tube is closed, but the change of shape in the tube, from a perfect cylinder into one having flat face and back, is brought about sharply by having the top of the tube-cup of proper width and curvature, so that the arcuate step properly dies out in the cylindrical portion of the tube without causing the tube to flatten so as to become of square area. The angle at which the sides of the top of the tube-cup are cut away to leave a curved top is of no particular importance as long as it is not interfering or retarding the forming of the arcuate step in the side of the tubes.

For a further exposition of my invention reference may be had to the annexed drawings and specification at the end whereof my invention will be specifically pointed out and claimed.

In the drawings,

Fig. 1 is a front or face view of one modification of my device.

Fig. 2 is a side view of the same modification.

Fig. 3 is an end view of the same modification.

Fig. 4 is a face or front view of the same modification showing the tube-cup and preformer.

Fig. 5 is a partial side view of the modification shown in Fig. 4.

Fig. 6 is an end view of the tube shown in Fig. 4

after it has been preformed but before it has been closed and folded.

Fig. 7 is a front or face view of another modification.

Fig. 8 is a partial side view of the modification shown in Fig. 7.

Fig. 9 is an end view of the tube shown in Fig. 7.

Figures 1, 2 and 3 clearly show the shape the tube I will take when closed according to this new and novel method. The arcuate step 7 dies out into the cylindrical part of the tube with a convex taper 5 ending at the end 6 of the straight fold 9. The outline of the tube as seen from the side in Fig. 2 forms a Gothic arc as it changes from the cylindrical portion 11 of the tube I into the relatively short, curved portion 8 at the fold 9, which fold may be of any type and may be either plain or corrugated. The arcuate step or arch 7 formed between the sides of the cylindrical portion 11 of the tube I and the ends 6 of the fold 9 is formed by the spreading and bending of the walls of the tube during the closing or folding operations. The arcuate step or arch 7 has its intermediate part 17 nearest fold 9 and has its end 18 curving away from fold 9 and is substantially smooth or regular.

Figs. 4, 5 and 6 show one process of closing the tube shown in Figs. 1, 2 and 3. This process consists in placing the cylindrical tube I in a tube-cup 26 having its upper end formed with arcuate or curved portions 21. A preformer consisting of central preformer blades or spreaders 32 are adjustably secured to the preformer by means of bolts and nuts cooperating with slots. The preformer also carries on the outside of the spreaders 32 centralizing and equalizing wings 31. The preformer spreads the top of the open end of tube I from a circular cross section into a generally rectangular cross section as seen in Fig. 6. The preformer then engages the top or open end of the tube between the spreaders 32 and the wings 31 and presses the tube I down against the arcuate portions 21 of the tube-cup 26 thereby forming arcuate steps or arches 7 in the walls of the tube. The preformer is then removed from the tube and the tube conveyed to another station of the machine where the open end is closed and folded in any convenient manner, as for example that set forth in my co-pending application for a Tube closing machine, filed June 21, 1933, Serial No. 676,911.

Figs. 7, 8 and 9 show another modification of the tube described above. The tube closed as shown in this way will not have a capacity quite as great as the previous one but has a slightly different appearance which may be more pleasing to certain users. The top of the tube-cup does not come quite as close to the top of the open end of the tube and the terminal point of the tube-cup is worked out to a different shape, having curves in both directions presenting a bow shape, so as to form a step 43 of less pronounced depth. The tube in being preformed by this new and novel method, while being supported in a tube-cup, takes a distinctly square outline with sides of convexo-concave outline in Fig. 9. The cylindrical portion 11 of tube I draws in at 40 and corners 48 form, extending outside the periphery of the cylindrical portion 11 as indicated clearly in Figure 8. The corners 48 are formed by the drawn-in portion 40 and the flattened face and back of the tube. To prevent the forming of dents by the natural tendency of the tube body to expand at the corners 48, the tube-cup in which these tubes are formed is relieved at the corners, 75

the high point being in between these relieved points in the shorter dimension. It should be noted that, as the tube is preformed, it takes the shape of an arc along its end, and the sides, in relationship to each other, also form into arcs when looking from the top of the tube in Figure 9. A definite relationship exists between the distance from the top of the tube-cup and the top or end of the open tube 1, which if exceeded one way or another has a tendency to deform the tube and cause wrinkles or dents in various parts of the tube body. The relationship between the relieved portions and the high points or top of the tube-cup is also definite for each size of tube.

15 A closed or finished tube is shown in Figs. 7 through 9 of this modified type. It should be noted that the convex taper 51 is somewhat longer in the modified tube, Figure 8, than in the previous one, Figure 2, and that the tube body 1 clearly 20 tapers in at 40, Figure 7.

Any type of fold or number of folds may, of course, be used with this modified type of tube closure and these may either be plain or corrugated.

25 I do not intend to be limited in the practice of my invention save as the scope of the prior art and of the attached claims may require.

I claim:

1. A process of forming a closure on collapsible

tubes, which process consists in the steps of, spreading the sides of the open end of a tube of substantially circular cross section until said open end assumes a substantially rectangular cross section, forming arcuate steps or arches in the sides of said tube by partially supporting said tube adjacent said open end on arcuate or arch shaped means and compressing the open end of said tube against said means by applying pressure to said tube internally and externally of said open end, 10 and closing and folding the open end of said tube.

2. A process of forming a closure on collapsible tubes, which process consists in the steps of, spreading the sides of the open end of a tube of substantially circular cross section until said open 15 end assumes a substantially elongated cross section having the longer sides bowed outwardly from the axis of said tube in cross section and bowed with the highest part in the center of said tube in side elevation, forming arcuate steps or 20 arches in the sides of said tube by partially supporting said tube adjacent said open end on arcuate or arch shaped means and compressing the open end of said tube against said means by applying pressure to said tube internally and externally of said open end, and closing and folding the 25 open end of said tube.

CHARLES J. WESTIN.
